Primary Examiner — Ricky Pham(74) *Attorney, Agent, or Firm* — Andrus Intellectual Property Law, LLP(57) **CLAIM**

The ornamental design for a wedger blade cover, as shown and described.

DESCRIPTION

FIG. 1 is a perspective view of a wedger blade cover; FIG. 2 is a top view thereof; FIG. 3 is a bottom view thereof; FIG. 4 is a right side view thereof; FIG. 5 is a left side view thereof; FIG. 6 is a front view thereof; and, FIG. 7 is a back view thereof.

The broken lines showing of various portions and other elements in the Figures are for the purpose of illustrating unclaimed portions and form no part of the claimed design.
